(57) **CLAIM**

The ornamental design for a head for a slotted turner, as shown and described.

DESCRIPTION

FIG. 1 is a perspective view of a head for a slotted turner according to the present invention, with a handle shown in broken lines

FIG. 2 is a front view of the slotted turner head shown in FIG. 1, with a handle shown in broken lines.

FIG. 3 is a rear view of the slotted turner head shown in FIGS. 1 and 2, with a handle shown in broken lines.

FIG. 4 is a side view of the slotted turner head shown in FIGS. 1-3, with a handle shown in broken lines; and, FIG. 5 is an end view of the slotted turner head shown in FIGS. 1-4.

The handle is shown in broken lines for illustrative purposes only and forms no part of the claimed design.
